UNITED STATES PATENT OFFICE.

EINAR MORTERUD, OF TORDEROD, NEAR MOSS, NORWAY, ASSIGNEE TO A/S CELLULOSEPATENTER, OF CHRISTIANIA, NORWAY.

PROCESS FOR DIGESTING WOOD PULP.

No Drawing.

Application filed March 4, 1919. Serial No. 280,657.

To all whom it may concern:

Be it known that I, EINAR MORTERUD, a subject of the King of Norway, of Torderod, near Moss, Norway, have invented certain new and useful improvements in Processes for Digesting Wood Pulp (for which I have filed applications for patents in Norway #11,850, filed Oct. 26, 1917, and in Sweden Dec. 31, 1918); and I do hereby 10 declare the following to be a full, clear, and exact description of the invention, such as will enable others skilled in the art to which it appertains to make and use the same.

By indirect heating of sulphite cellulose 15 digestors the heating surface used will have tendency to be covered with precipitated chalk compounds. This covering is of great disadvantage when its thickness can not be controlled. 20 The said precipitation on the heating surface according to the experience of the inventor may be counteracted by different methods, but the most efficient method is the one, which consists in establishing a 25 pressure on the digesting liquids from the beginning of the digesting operation, which pressure is higher than the pressure caused by the temperature of the digesting liquid and maintaining such pressure during the 30 digestion.

Said pressure is obtained most practically by filling the digestor completely or almost completely with liquid, so that the development of a small quantity of gas will at once 35 control the pressure conditions.

Experience has shown that the conditions of pressure has a great influence on the forming of precipitated covering, the reason for this fact being probably that the chalk 40 compounds, which are maintained in solution by means of the free SO_2 , are liable to precipitate when the gas is liberated from the liquid owing to rise of temperature or emptying of the digestor. Such liberating 45 of gas observed in the liquid, as it will be known, takes place when the pressure in the liquid increases.

The pressure is obtained by filling the digestor as full as practically possible with

liquid before the digesting process begins so and maintaining it full during the process.

Naturally, if the digester is full of liquid and pulp at the beginning of the operation the pulp will absorb much liquid, and the level will sink thus forming a space above the level in the digester for the collection of gas. The formation of this space must be prevented by pumping in under pressure sufficient liquid to compensate for that absorbed, this may be either hot or cold liquor from an adjacent digester in which the process has progressed beyond the danger of carbonizing the pulp.

Of course, it is understood that in the indirect cooking method there is no addition of liquid due to the condensation of steam directly introduced into the contents of the digester for the purpose of heating its contents.

This obviates the disadvantage of the direct cooking method where liquor and gas have to be vented from the top of the digester from time to time, in order to reduce the pressure sufficiently to permit the cooking steam to enter at the bottom of the digester.

I claim:

The method of preventing the separation of calcium compounds from the digesting liquid due to the liberation of gas therefrom during the indirect digestion of sulphite cellulose, which comprises maintaining the liquid under a pressure in the digester during heating greater than the pressure permitting the liberation of gas from the liquor, thereby permitting the liberation of any substantial quantities of gas above the surface of the liquor in the digester, and substantially preventing the liberation of calcium salts that form a thick scum thereof over the surface of the digesting liquor.

In testimony that I claim the foregoing as my invention, I have signed my name in presence of two subscribing witnesses.

EINAR MORTERUD.
